DISPLAY CABINET

Robert B. Welch, Portland, Oreg., assignor to Revolva Products, Inc., Portland, Oreg., a corporation of Oregon

Application December 6, 1954, Serial No. 473,229

2 Claims. (Cl. 312—120)

This invention relates to display racks and particularly to devices of this kind which are adapted to be used to display numerous items of the same general character whereby a number of these items may be displayed simultaneously or selected ones may be displayed simultaneously.

For example, it has been found that in the displaying of certain items such as cremation urns, burial markers and stones, etc. it is desirable to have exemplars of each of the various types and styles of devices available for display without having them displayed in such great abundance as to confuse the purchaser or result in a cluttered sales or display room. In addition where numerous similar devices of this kind are to be displayed, they vary in price, size, and in other ways, and a salesman may desire to direct the prospective purchaser's attention to particular sizes or styles or to devices in a particular price range without having to display other devices. Moreover, under other conditions it may be desirable to display one, two or many of the devices simultaneously or, in order to assist the purchaser in narrowing his selection, to display only two, for example, of the devices simultaneously.

It is an object of this invention to provide a type of supply and storage device which, when it is in inoperative position will effectively conceal all of the devices to be displayed and will present merely a panelled surface broken by the outlines of the storage or display cells or units.

It is a further object of this invention to provide a device of this kind in which selected cells or units may be opened or closed that is, turned to operative or display position or returned to inoperative or storage position.

It is a further object of this invention to provide groups of storage or display cells or units which may be joined together with any pre-determined pattern of sizes.

Other objects and advantages will appear from the following specification taken in conjunction with the accompanying drawings in which:

Figure 1 represents a front view of a plurality of my display and storage units placed against a wall, for example;

Figure 2 represents a cross sectional detail taken along the line 2—2 of Figure 1;

Figure 3 represents a cross sectional detail taken along the line 3—3 of Figure 2;

Figure 4 represents a cross sectional detail taken along the line 4—4 of Figure 1; and

Figure 5 represents a modification of a device illustrated in Figures 1 and 2 and particularly in that a small display cell is provided in the face of the unit.

As illustrated in Figure 1 my device consists of a plurality of similar, and in some cases identical, storage or display units 10, each of which is provided with a front panel 11. The front panels 11 of all of the members 10 may be made of similar material and, as shown in Figures 1, 2, 3 and 4, an opaque material, so that when a plurality of them are positioned as illustrated in Figure 1, they form a pleasing and harmonious surface. I have

2

found that matched wood surfaces give a most harmonious and pleasing effect.

The units 10 may ultimately be made in any particular size and shape and the arrangement illustrated in Figure 1 is illustrative only. For example, it should be noted that those members illustrated in Figure 1 rest upon lower or bottom cabinets 12 which are provided with hinged doors 13.

As illustrated particularly in Figures 2 and 4 each of the cells 10 comprises generally a five sided enclosure consisting of a rear wall 16, a pair of side walls 17, bottom wall 18 and top wall 19. This five sided member may be formed of metal or wood, or in some cases of plastic, the particular material being a matter of little consequence, provided, however, that the material is sufficiently sturdy for the purpose for which it is intended. As illustrated herein walls are made of metal and provide a rigid assembly. The front wall 11 may be secured to the rear wall 16 in any suitable manner as, for example, by the screws 21. The lower wall 18 is shown provided with an extension 18a which, together with the wall 18, is adapted to support the merchandise or other items to be displayed.

The assembly or unit 10 is mounted for rotation about the axis 22. A metal pad 23 may be fastened to the lower wall 18. It may, in turn, rest upon a similar pad 24 which is secured to a horizontal framework structure 26. A threaded member 27 is secured to the under side of the pad 27 in any suitable manner as, for example, by welding, and is adapted to receive a similarly and cooperatively threaded member 28. The member 28 is accommodated in a recess in the members 18 and 23 and forms a lower pivot about which the cell 10 may rotate. The upper wall 19 is provided with a similar pad 31. A pad 32 is secured to an upper parallel horizontal member 26 and is also provided with a threaded member 33 which is secured thereto. A bolt 34 which is accommodated within a recess in the members 19 and 31 is threadedly mounted in the member 33 and provides an upper pivot for the cell or unit.

It will be noted that the axis of rotation of the member 10 is equidistant from the sides of the opening within which the unit is mounted. However the axis of rotation is also such that when the unit is moved from the position illustrated in Figure 1 through the dotted line position illustrated in Figure 2, a substantial portion of the side walls 17 and the bottom wall 18 and its extension 18a extend forwardly of the entire assembly of units in such a manner that the merchandise or other articles mounted on the floor 18 and 18a is projected forwardly from the wall illustrated in Figure 1.

I provide a stop 36 which is secured to the lower structural member 26. A pair of depending stops 37 and 38 are provided on the unit 10. Stop 37 is so positioned that when the device is in inoperative or non-display position it engages the stop 36 and retains the unit in substantially the position illustrated in Figures 1 and 2. Stop 38 is so positioned, however, that when the device is in operative or display position, it engages the stop 36 and retains the unit in pre-determined proper display position.

The units 10 are adapted to be supported on a framework which consists generally of a plurality of vertical and horizontal members. The horizontal members 26 have previously been pointed out and described and they support the units or cells. The members 41 form vertical supports for the horizontal members 26. Both the members 26 and 41 are provided with an exposed molding 42 which serves to enhance the beauty of the entire assembly.

The members 42 and the surfaces 11 may be formed of the same material so that they present a more or less uniform appearance or, they may be made of different material to provide various designs. At any rate, how-

ever, they combine to form a substantially planar surface when all of the members 10 are in inoperative or storage position as illustrated generally in Figure 1.

Operation of the device may briefly be described as follows: Let it be assumed that a number of articles are to be displayed. I should state at this point, that they may be of any type of article which is adapted to be merchandised by display including, but not limited to, jewelry, precious items, china, silverware and glassware, cremation urns, etc. These items are placed in suitable members 10 as shown in Figure 4. When the members or units 10 are in inoperative or storage position as illustrated in the upper portion of Figure 4, the surfaces 11 will combine to provide a substantially planar and uniform front, and all of the members which are to be displayed are concealed. When it is desired that a particular item be displayed however, specified members 10 may be rotated about their axes 22 so that the member is displayed as illustrated in the lower portion of Figure 4, that is, with the floor portion of the cell 18 extending forwardly of the general plane of the members 11 and with the displayed member positioned generally in a suitable display position. By altering its specific position upon the floor 18 or the extension 18a, of course, the article to be displayed may be urged forwardly into the area immediately in front of the wall formed by the members 11 or, if it is an item which is more exotically displayed by being recessed, it may be positioned on the floor 18 in such a manner that it appears to be recessed.

The unit 10 is rotated until the stop 38 engages the stop 36 at which time the wall 11 of the rotated member is substantially parallel to the position which it occupied in the non-display position. When it is desired that that particular item no longer be displayed, the unit 10 may again be rotated about the axis 22 until the stop 37 engages the stop 36 at which time the surface 11 will again occupy the same plane as the other surfaces 11 when in non-display position.

In the modification illustrated in Figure 5, I have provided a modification in which the wall 11 is provided with a recess 51. The recess 51 is surrounded on five sides by opaque walls 52 and on the front side is provided with a transparent member 53 so that the contents of the area 51 may be observed. The area 18 provides a storage space. This modification is particularly adaptable for use in connection with the merchandising of small items, a single exemplar of which may be placed in the area 51 for observation. While the device may be observed it will, of course, be beyond the reach of prying fingers and shop lifters. On the other hand, a plurality of similar items may be retained on the storage space formed by the floor 18 so that when a customer has selected a particular item, the unit 10 displaying such an item in its display area 51 may simply be rotated in the manner previously described and one of the similar items removed from the storage area 18.

I claim:

1. In a display cabinet, a framework including a plurality of horizontal and vertical members defining a plurality of recesses, the front edges of said horizontal and vertical members defining a vertical plane, said framework also including a molding secured to the front edges of said horizontal and vertical members to form a planar front wall having openings therein communicating with said recesses, a display unit mounted in each of said recesses, each of said display units comprising a rear wall, horizontal top and bottom walls, and a pair of vertical side walls defining an open-faced display cubical, a front panel mounted on said rear wall, each of said front panels and rear wall having an opening therein, a transparent member mounted in said front panel and closing the opening in said front panel, an opaque three-sided member mounted in the opening in said rear wall and front panel to the rear of said transparent member, said three-sided member having an open end facing the transparent member so that articles stored within the three-sided member may be viewed through the transparent member, means for pivotally mounting said display units in said recesses upon said horizontal members whereby said display units may be rotated between open and closed positions, in the closed position the front panel mounted on the rear wall of the display unit being flush with the molding forming the front wall of the framework, and in an open position the open face of the display cubical facing the opening communicating with the recess.

2. A display cabinet as in claim 1 together with a pair of stops mounted on each of said display units, and a third stop mounted on said framework within each of said recesses, one of the first named stops being adapted to engage said third stop when the display unit is in a closed position and the other of said first named stops being adapted to engage said third stop when the display unit is in an open position, and wherein said bottom walls of each display unit is provided with an extended portion, the extended portion projecting through and extending beyond the opening in the front wall communicating with the recess when the display unit is in an open position.
